TREATMENT OF HYDROCARBON OILS

Jean Delattre Seguy, Chicago, Ill., assignor to
 Universal Oil Products Company, Chicago, Ill.,
 a corporation of South Dakota

Application July 26, 1930. Serial No. 470,849

3 Claims. (Cl. 196—60)

This invention relates to the treatment of hydrocarbon oils and pertains more particularly to improvements in the art of cracking.

The invention in one of its forms relates to a process for cracking hydrocarbon oils wherein the oil undergoing treatment is subjected to a suitable conversion under the desired conditions of temperature and pressure, the vapors and unvaporized residue produced from the conversion being subsequently subjected to further treatment.

In one of the preferred embodiments of the invention, the oil under treatment is subjected to conditions which will induce cracking, being then withdrawn into a distillation zone wherein are separated vapors and unvaporized residue, at least a portion of the vapors being separately subjected to further conversion and returned to the distillation zone to assist in controlling the temperature therein and to contribute to the regulation of the character of the product produced by the distillation.

Further objects of the invention will become evident from the following detailed description of the invention.

Referring to the drawing which is diagrammatic and not to scale and is illustrative of one form of apparatus suitable for carrying out the operation of the process of the invention, the raw oil charging stock is pumped through line 1, valve 2 by means of pump 3 through valve 4, line 5 into the fractionating column 6 where it undergoes heat exchange with the vapors arising therein and assist in the cooling and fractionating of said vapors.

The reflex condensate formed in 6 passes through line 7, valve 8, line 9 and is pumped by means of hot oil pump 10 through valve 11 line 12 into heating element 13 located in furnace setting 14. The oil at the conversion temperature is discharged from heating element 13 through line 15 and may be passed through line 16, valve 17 into the reaction chamber 18, the contents of which are discharged through line 19, valve 20 into line 21 through valve 22 and into flashing and coking chamber 23. A portion or all of the oil may be passed through line 24, valve 25, line 21, valve 22 into the flashing and coking chamber 23. A small amount of steam may be introduced into the chamber 23 through line 26 controlled by valve 27.

Vapors leaving the flashing and coking chamber 23 pass through vapor line 28 controlled by valve 29 and are passed into the fractionating column 6 where the heavier intermediate boiling

components or reflux condensate are formed and returned to the heating element 13 as described.

A portion of the vapors from chamber 23 is circulated through line 30 controlled by valve 31 by means of pump 32 through control valve 33 into secondary heating element 13' and through valve 34, line 35, valve 36 back into the flashing and coking chamber 23. The purpose of circulating the vapors is two-fold, namely, to supply heat to the flashing and coking chamber 23 in addition to bringing about further conversion of the vapors leaving 23 into hydrocarbons having anti-knock properties thus increasing the value of the motor fuel produced by the process.

A portion of the vapors leaving heating element 13' may pass directly to fractionating column 6 through line 54 having valve 55. This permits controlling the quantity of vapors to return to chamber 23.

A portion of the charging stock may be fed direct by pump 3 through valve 37 and line 38 into the hot oil pump 10 and subsequently into the heating element 13. The vapors leaving the fractionating column 6 pass through line 39, valve 40 into cooler and condenser 41. The products pass through line 42, valve 43 into receiver 44 and the liquid may be withdrawn from receiver 44 through line 45 controlled by valve 46. The vapors are discharged through line 47 controlled by valve 48.

A portion of the liquid in receiver 44 may be recirculated through line 49 controlled by valve 50, by means of pump 51 through valve 52 and line 53 into fractionating column 6 where it assists in fractionating the vapors therein and regulating the boiling range of the products leaving the same.

I may use temperatures in the heating element 13 of approximately 800 degrees F. to 1000 degrees F. and temperatures in the heating element 13' of approximately 900 degrees F. to 1300 degrees F. more or less. Differential pressures may be used between the heating element 13 and the succeeding elements such as the reaction chamber, flashing and coking chamber, fractionating column, condenser and receiver or the pressures on the heating element 13 may be equalized with respect to the reaction chamber 18 with preferably reduced pressures on flashing and coking chamber 23, fractionating column 6 and heating element 13' as well as on the condenser and receiver.

As a specific example of the results obtained by the operation of the process of my invention, a 22° A. P. I. gravity fuel oil was treated using

a temperature of approximately 885 degrees F. in the heating element 13, passing the heated oil through the reaction chamber 18 and discharging the same through line 21 into the flashing and coking chamber 23.

The pressure on the heating element 13 and reaction chamber 18 was maintained at about 200 pounds per square inch. The pressure on the flashing and coking chamber 23 was maintained 10 at approximately 50 pounds per square inch. That on the fractionating column was substantially equalized with the pressure in the coking chamber. The temperature in the heating element 13' was maintained at approximately 950 15 degrees F., the pressure on element 13' being preferably equalized with that on the flashing chamber 23.

A yield 50 per cent gasoline having an anti-knock value of approximately 55 per cent 20 benzol equivalent, that is equivalent to the mixture of Pennsylvania straight run gasoline and benzol containing 55 per cent of the latter, was obtained. In addition 35 per cent of fuel oil residue meeting market requirements with respect to viscosity and low B. S. content, 5 per 25 cent of pressure distillate bottoms was obtained, the remainder being coke and gas.

When the oil leaving the heating element 13 was by-passed directly into the flashing and coking chamber 23 the through-put or capacity of 30 the plant was reduced but the above yields could be maintained by increasing fuel consumption and reduced capacity.

When the temperature on the heating element 35 13 was increased to approximately 920 degrees F. and the temperature in 13' to approximately 1000 degrees F., operating the plant at a somewhat smaller capacity and maintaining the pressure conditions in heating element 13 and chamber 40 18 the same as stated, 60 per cent of motor fuel having a benzol equivalent of 60 per cent was obtained. Approximately 10 per cent pressure distillate bottoms was made. Approximately 45 60 pounds of coke per barrel of oil charged was produced in the chamber 23 and the remainder was gas. In this operation, as in that first described, the reaction chamber 18 was utilized. When the reaction chamber was by-passed, maintaining the temperature conditions as stated, the 50 oil could be readily reduced to coke but the capacity and yield of gasoline was somewhat diminished.

During the coking operations the pressure on the chamber 23 was maintained at approximately 55 20 pounds per square inch, this pressure being equalized with that in the heating element 13' and the fractionating column 6.

With temperatures intermediate to those shown 60 for the fuel oil and coking operations, a residue suitable for asphalt could be produced.

I claim as my invention:

1. A hydrocarbon oil cracking process which comprises passing the oil in a restricted stream

through a heating zone and heating the same therein to cracking temperature under pressure, transferring the heated oil from the heating zone to a reaction zone maintained under cracking conditions of temperature and pressure wherein 80 the velocity of the oil is materially reduced, continuously removing unvaporized oil from said reaction zone and flash distilling the same in a flashing zone by pressure reduction, removing the resultant flashed vapors from the flashing zone and passing a portion thereof, prior to condensation, to a vapor phase cracking zone, heating said portion of the flashed vapors to vapor phase cracking temperature in said cracking zone and introducing the thus heated vapors into the unvaporized oil undergoing distillation in said flashing zone to augment the vaporization thereof, and condensing the remaining portion of the flashed vapors removed from said flashing zone. 90

2. A hydrocarbon oil cracking process which 95 comprises passing the oil in a restricted stream through a heating zone and heating the same therein to cracking temperature under pressure, transferring the heated oil from the heating zone to a reaction zone maintained under cracking 100 conditions of temperature and pressure wherein the velocity of the oil is materially reduced, continuously removing unvaporized oil from said reaction zone and flash distilling the same in a flashing zone by pressure reduction, removing 105 the resultant flashed vapors from the flashing zone, and passing a portion thereof, prior to condensation, to a vapor phase cracking zone, heating said portion of the flashed vapors to vapor phase cracking temperature in said cracking zone 110 and introducing the thus heated vapors into the unvaporized oil undergoing distillation in said flashing zone to augment the vaporization thereof, dephlegmating the remaining portion of the flashed vapors removed from said flashing zone and returning resultant reflux condensate to the heating zone for recycling through the process, and finally condensing the dephlegmated vapors. 115

3. In processes for cracking hydrocarbon oil 120 of the character in which the oil is heated to a cracking temperature in a coil, thence delivered to an enlarged reaction chamber wherein the velocity of the oil is materially reduced and from which unvaporized oil is passed to a zone of lower 125 pressure to effect distillation thereof by the contained heat of the oil and vapors evolved from the oil subjected to condensation and collection, the improvement which comprises subjecting a portion of the hydrocarbons separated as vapor 130 from the unvaporized oil by the reduction in pressure to vapor phase cracking conditions and reintroducing such portion subsequent to subjecting to vapor phase cracking conditions to the body of oil undergoing vaporization in said zone 135 of reduced pressure.
